UNITED STATES PATENT OFFICE.

WILBUR H. PECK, OF LOS ANGELES, CALIFORNIA.

MEANS AND APPARATUS FOR CENTRIFUGAL CONCENTRATION AND SEPARATION OF MIXED MINERALS, METALS, ETC.

Application filed March 2, 1922, Serial No. 540,463. Renewed December 8, 1924.

To all whom it may concern:

Be it known that I, WILBUR H. PECK, of Los Angeles, California, having invented certain new and useful improvements in 5 means and apparatus for centrifugal concentration and separation of mixed minerals, metals, and metal-bearing mixtures while in a fused state, and my invention consists mainly in the means and apparatus 10 embodying the association and cooperation of parts to effectuate such separation, as herein described and claimed and illustrated in the accompanying drawing, in which—

15 Fig. 1 is mainly a central vertical cross section of my separator.

Fig. 2 is mostly a central transverse plan section of the rotating parts of my separator, shown in Fig. 1, looking downward, 20 most clearly illustrating the two separating vessels in section, but with the central feed device illustrated in top plan.

Fig. 3 is mostly a central transverse vertical section of the rotor of my separator, 25 with some of the members of the same shown somewhat relatively moved apart.

Fig. 4 is an outside elevation of an enlarged fragmentary part of the peripheral ring of the rotor, showing the outer ends of 30 water channels and opening through which material passes as discharged from the vessel.

Fig. 5 is a central longitudinal horizontal section of the feed device of my separator.

35 Fig. 6 is a cross section of Fig. 5 on line 6—6 of Fig. 5, looking in the direction of the arrows.

Fig. 7 is a cross section of one of the separating vessels, shown partly withdrawn 40 from the reinforcing casing.

Fig. 8 is a central longitudinal section of a fragmentary part of the reinforcing casing, illustrating the inside ribbed or corrugated form.

45 Fig. 9 is a top plan of one of the separating vessels inserted in its reinforcing casing.

Fig. 10 is a transverse section of Fig. 9 on line 10—10, of Fig. 9 looking in the direction of the arrows.

50 Fig. 11 is a cross section of Fig. 9 on line

11—11 of Fig. 9, looking in the direction of the arrows.

In making my centrifugal fused ore separator, I provide means for subjecting such fused ore or materials to the action of centrifugal force of sufficient intensity to effect separation of the fused mixture into its constituent parts to the extent sought, and accomplish the desired objects while the material is being carried around in rotation 55 and at the same time is also being flowed in a circumferential direction in the path of rotation, preferably in a forward or advanced direction with respect to such rotation, and to this end:

I provide a suitable shaft 2 for supporting and rotating the desired part of the separator. This shaft is maintained laterally at its upper end portion by a journal box 3, and at its lower portion by the 60 box 4. It is also suitably stepped at its lower end in the lower part of the box 4, to support and carry the weight of the shaft and its burden.

The box 4 is flexibly supported by a base 65 plate 5 through an interposed flexible member 6, illustrated in Fig. 1, as a rubber cushion, to permit gyratory movement of the box and shaft, if that should occur during operation.

The box 3 is also flexibly supported by a frame part 7, through means of an interposed yieldable member, as a rubber cushion 8, so the shaft at its upper end may gyrate or vibrate to compensate for any 70 unevenness, if any there may be, in the distribution of the materials fed to the separating vessel. The rubber 8, is clamped under the ring plate 9, which helps to hold it in place.

The frame is mounted at its lower portion on the base of the machine, as illustrated in Fig. 1, and the shaft is provided with a pulley 10, through which rotation may be imparted by a belt from any desired source 75 of supply of power.

Mounted on the upper end of the shaft through means of an attached hub portion 11, is a disc member 12 preferably comprised of two plates, having one or more 80

100

water channels 13 between them, radiating from near the central portion of the disc. Near the axis and secured to the lower side of the disc is provided a suitably shaped 5 ring 14 adapted to form an annular channel 15, suitable to receive water from a water delivery pipe 16, and to divert the same through openings 17 into the channel 13, between the plates forming the disc, so the 10 water will pass out through the channels and serve to cool the disc during operation.

Around the circumferential portion of the disc, which serves as a supporting member, is located a ring 18, as illustrated in the 15 drawings, of desired width, which is carried around the circumferential portion of the disc, and extends upward a sufficient distance to receive below its upper edge, separating vessels 19, when the same are in place on 20 the disc, as especially illustrated in Fig. 1. The ring is intended to be of sufficient strength to support the vessels against the action of centrifugal force during operation, and adapted to otherwise assist in holding 25 them to place.

The vessels, which may also be termed 30 containers are preferably segmental, and rectangular in form as best shown in Figs. 1 and 9, thereby predetermining and limiting the arc in which the fused materials 35 may flow during treatment and are intended to be of peripheral contour to rest and contact against the inner circumference of the ring 18, when they are in operating position, extending circumferentially lengthways in the arc or path of rotation.

There are preferably two or more of the 40 separating vessels employed, which together with their supporting parts and the feed device 32, largely make up the rotor of the separator. They are intended to be of as 45 nearly uniform size, weight and containing capacity as practicable in order to as nearly as may be, form a balanced condition of the rotor during operation. They are intended to be of sufficient thickness and strength to serve the purposes for which they are designed, and of height, as above 50 stated, to correspond with the height or width of the ring, when the latter is in position.

At the ends of the separating vessel, there 55 are discharge passages 21 and 22 respectively, for discharge of the fused material. These passages are formed by cutting out or suitably lowering a portion of the end wall of the vessel, as illustrated in Figs. 2, 9, 10 and 11; the passage 21 approaching to a position nearer the bottom of the vessel 60 than the passage 22, it being intended for discharge of the metals or separated heavier materials, while the passage 22 is intended for the outflow of the relatively lighter portions of the separated materials.

65 The passage 21 for discharge of the sep-

arated heavier materials is intended to be located at the end of the vessel which follows in the direction of rotation, while the passage for the relatively lighter material leads in rotation. These positions are 70 illustrated in Fig. 2, the separator being adapted to revolve clockwise.

There are passages, 23 and 24, formed at the ends of the vessel, communicating with the separate overflow or discharge passages 75 21 and 22, which are adapted to receive the fused materials as it flows from the vessels, and divert the same through the ports 25 and 26, in the ring 18, and into appropriate compartments 27 and 28, of a housing 29. 80

The separating vessels are each provided with a cross baffle 30, which are located nearest the end from which it is intended to discharge the heavier material. These baffles or cross-partitions extend somewhat 85 above the surface of the fused material in the vessel while in operation, and serve to deflect the surface portion and separated relatively lighter constituents of the fused mixture forward in the path of rotation 90 towards the discharge passage 22, in the leading portion of the vessel, but do not extend to the bottom of the vessel or container, leaving a passage 31 under their lower edges, as illustrated in Fig. 2, which 95 passages are positioned beneath the surface or normal level of the fused mixture in the container during operation, and serve as passages through which the separated heavier or lower strata of material may 100 flow backward with relation to rotating movement and surface flow of lighter constituents, to discharge through the passages 21.

It will be seen that this structure of the 105 vessel or container with its discharge passages and the cross baffle 30, constitute means during rotation for effecting separation of constituent of the fused mixture, and at the same time for effecting relative flow 110 of the surface or upper and under portions of the fused material in the container in relatively opposite directions within the limits of the arc predetermined by the structure of the container, and for the separate 115 and simultaneous discharge of such portions of the material being treated.

As means for supplying fused material to the separating vessels, I provide a feed member 32, located axially between them. 120 This feed member embodies a central part with a chamber 33, and also has two extended hollow arms 34, of suitable length and size to terminate in position to deliver fused material passing through them to a 125 position near the baffle, and at the side of the baffle towards the end of the vessel where it is intended to discharge the lighter material.

The feed member is also provided with a 130

portion 36, preferably made along and integral with the arms 34, as illustrated in Figs. 2 and 6, and these parts 36 are also provided with passages 37, as shown, for the flow of water for cooling the feed member 32.

The cooling passages 37 connect with a feed water chamber 38 surrounding the feed chamber 33, and there is a pipe 39, Figs. 1 10 and 2, by which water may be supplied to the chamber 37. The parts 36 are provided with a downwardly projecting, preferably right angular extension 40, near their outer ends, through which the channels 37 pass, 15 as shown in Fig. 6, and terminate in a recess 41, shown in Figs. 1 and 3, in the disc 12, in position to deliver cooling water flowing through them into the channels 13 in said disc.

20 These extensions also assist in holding the feed member properly to place, as does also a central lower extended gudgeon 42, which seats in the central chamber of a member 43, attached to the disc 12 as illustrated.

25 In Fig. 1 fused material 44 is illustrated as being introduced into the feed chamber 33, for delivery through the passages 35, into the separating vessels, and at such times water flowed through the channels 37, will 30 prevent the feed member from becoming greatly overheated.

The separating vessels are provided with suitable covers 45, which have an appropriately located opening, 46, through which the 35 material is delivered into the vessels. The cover is intended to be easily removable when the vessels are taken out of the rotor.

To serve as a reinforcing member to the separating vessel there is provided a casing 40 47, which is of internal contour and size to closely receive the vessel, serving to strengthen the vessel, and also through its internal corrugation, when in place on the vessel, forms air spaces 48, which reduces 45 heat radiation from the vessel.

As means for assisting to hold the separating vessels in place and to cover the same to afford a more symmetrical outer surface to the rotor, I provide a disc or ring plate 50 49, seated on the upper edge of the ring 18, as shown in place in Fig. 1 of the drawings. This plate has a suitable size central opening through which access may be had, and to enable introduction of materials for separation. The plate is held securely and removably to place by bolts 50.

Surrounding the rotor of the separator to collect material discharged from the separating vessels, and water used in connection 60 with the same, as above stated, I provide a suitable housing 29 having an inclined bottom and two annular compartments 27 and 28, into which the separated materials are discharged.

65 These compartments are provided at their

tops with covers 51 and 52, and there is located in them water spray pipes 53 and 54 for spraying and cooling the material as it enters the compartments passing through the parts 25 and 26, which deliver the respective lighter and heavier materials in their appropriate compartments; to enable the same with the water to pass out through the discharge openings 55 and 56.

The housing may be held in place by a bracket 57 or by any desired suitable means.

In operation, fused materials such as mixed metals or mineral bearing ores, matter or other metal or mineral bearing compounds which are amenable to separation or concentration by centrifugal force, are flowed into the central feed chamber 33, while the rotor is being operated at a desired speed, and is delivered by the feed member into the separating vessels, as illustrated, in position near the baffles 30, on the side of the baffles towards the discharge passage for the lighter material. The distance from the baffle to this discharge passage is intended to be much greater than the distance to the discharge for the heavier material, as the greater distance is desired through which to flow the material to enable better separation.

The baffles serve as means to divert the 95 surface flow of the fused material being fed into the vessel, in direction towards the end of the vessel for the discharge of the relatively lighter parts, preventing such flow to pass towards the opposite end. 100 It is intended that this direction of flow shall be with or in direction of rotation, and that the material is therefore not only carried around in rotation in the separating vessel, but at the same time the surface 105 portion of the material in the end compartment, where it is fed in, is flowing against such rotation to the discharge passage in the forward end of the vessel, while the heavier parts or constituents of the 110 fused mass which are separated, are precipitated towards the bottom of the vessel radially, from the axis, where it accumulates in sufficient body to pass under the baffle in the vessel and flow to discharge 115 at the back or following end of the vessel through the passage which is cut down, or approaches nearer the bottom of the vessel.

The heavier material in the latter end 120 with a shallower deposit or lower column in the vessel, balances the lighter material on the opposite side of the baffle, with a higher column and the two automatically adjust themselves to effect proper separate 125 discharge from the vessel at their appropriate discharge passages. The level or surface of the two classes of materials are indicated by the initial numerals 58 and 59 in Fig. 2.

What I regard as new and desire to secure by Letters Patent is:—

1. In a centrifugal separator adapted to treatment of fused material having metal bearing constituents, the combination of a container adapted to rotate said material while in a state of fusion, means for feeding fused material to the container, means within the container for diverting the flow of the surface and bottom portions of the fused material in the container in relatively opposite directions along the path of rotation of the container while separation is being effected, and means for discharging separately from the container separated heavier and lighter constituents of said material, substantially as described. 70
2. In a centrifugal separator adapted to treatment of fused material having metal bearing constituents, the combination of a container adapted to rotate said material while in a fused state in structure forming an arc of predetermined extent and having a discharge passage for relatively lighter of said constituents in its portion leading in rotation, and a discharge passage for relatively heavier constituents of said mixture positioned following the above stated passage, means within the container for diverting the surface portion of the fused material forward in direction of rotation towards said leading discharge passage within the limits of the arc predetermined by the structure of said container, means 80 30 through instrumentality of the structure of the container and discharge passages for separately and simultaneously discharging from the container separated relatively heavier and lighter constituents of said material and means for feeding fused material to the container, substantially as described. 85
3. In a centrifugal separator adapted to treatment of fused material embodying metal bearing constituents, the combination of a container adapted to rotate said material, means for feeding the fused material into the container, means for effecting the flow of the surface and under portions of the fused material in the container in relatively opposite directions along the path of rotation of the container, means for separately discharging separated fused relatively heavier and lighter constituents of the material and means for supporting and rotating the container, substantially as described. 90
4. In a centrifugal separator adapted to treatment of fused material embodying metal bearing constituents, the combination of a rotatable elongated, segmental separating vessel, means for feeding fused material into such vessel, means for diverting surface flow of fused material in the vessel in direction of rotation of said vessel, means 95 50 for discharging separately separated fused constituents of relatively different specific weights from the vessel, and means for supporting and rotating the vessel substantially as described. 100
5. In a centrifugal separator adapted to treatment of fused mineral bearing mixtures, the combination of a rotatable container in longitudinal structure forming an arc of predetermined extent, adapted to carry such mixture in rotation while in a state of fusion, said container provided with a discharge passage for the surface part of said fused material positioned in the portion thereof leading in direction of rotation, and with a discharge passage for relatively heavier material in the portion of said container following in rotation, a partition in the container positioned between said respective discharge passages, having a channel beneath the normal surface of the fused material during operation for flow of relatively heavier material, whereby the surface portion of said material is diverted forward in direction of rotation during separation within limits of the arc predetermined by the structure of said container, and the bottom portion of the fused material is flowed relatively backward in the path of rotation, means embodying said passages for discharge separately of relatively heavier and lighter constituents of the fused material, means for feeding fused material into the container between said partition and the discharge passage leading in rotation and means for supporting and rotating the container, substantially as described. 105
6. In a centrifugal separator adapted to treatment of fused mineral bearing mixtures, the combination of a rotatable container adapted to carry such mixtures in rotation while in a state of fusion and in structure forming an arc of predetermined extent, for centrifugally effecting separation of relatively heavier and lighter constituents of said mixture, said container provided with a passage positioned in its portion leading in rotation, for discharge of relatively lighter constituents of said mixture, and a passage for discharge of relatively heavier constituents of said mixture in its portion following in rotation, and means constituted by the structure of said container with said discharge passages and a diverting baffle positioned within the container, for effecting simultaneous flow of heavier and lighter constituents of said mixture in the container in relatively opposite directions in the path of rotation within the limits of said arc predetermined by the structure of the container, and for separately discharging said separated constituents, substantially as described. 110
7. In a centrifugal separator adapted to 115 60 65 70 75 80 85 90 95 100 105 110 115 120 125 130

treatment of fused metal bearing mixture, the combination of multiple segmental vessels having separate discharge passages for separated relatively heavier and lighter constituents of said mixture, means adapted to feed the fused mixture to the vessels, means for supporting and rotating the vessels, a rotatable ring adapted to support the vessels against centrifugal stress, means for discharging from the vessels separately separated relatively heavier and lighter constituents of said mixture, and means for catching separately said heavier and lighter constituents as discharged from the vessels substantially as described.

8. In a centrifugal separator adapted to

treatment of fused metal bearing mixtures, the combination of multiple segmental rotatable vessels having separate discharge means for the separated relatively heavier and lighter constituents of said mixture, means for feeding fused material to the vessel, means for supporting and rotating said vessels, embodying disc and shaft mechanism, a ring peripherally encircling said vessels adapted to maintain the vessel against centrifugal stress, and means for receiving separately said separated relatively heavier and lighter constituents as discharged from the same substantially as described. 20 25 30

WILBUR H. PECK.
